MACHINE GUN FEED MECHANISM

John C. Trotter, Williamsville, N. Y., assignor to
Bell Aircraft Corporation, Buffalo, N. Y.

Application February 7, 1941, Serial No. 377,819

4 Claims. (Cl. 89—33)

This invention relates to machine guns, and more particularly to improved means for feeding of ammunition thereto.

Modern machine gun installation designs tend to involve provision for continuously increasing ammunition magazine capacities, whereby the cartridge belts are required to be pulled over increased distances and the loads upon the gun feed mechanisms are consequently increased. Also, because of the modern tendency to increase the caliber of the cartridges used, the weights of the cartridge belts are also thereby increased, and the gun feeding mechanisms are required to supply substantial amounts of power to the moving of the cartridge belts. Because of definite limitations with respect to strength and power supplying abilities of the usual gun feed mechanism per se, I have found that it is of utmost importance and desirability to supplement the action of the usual gun feed mechanism by means of an accessory feed assist mechanism so that previous limitations as to location of the magazine relative to the gun are no longer deciding factors with respect to the design of the gun and gun feed installation. This is of particular importance, for example, in connection with modern combat airplane construction because of certain space limitations which are inherently present in connection with airplane design.

The present invention contemplates the disposition of the cartridge belt magazine at any desired location relative to the gun, as for example at a relatively remote location within an enclosing airplane wing structure or the like; and the magazine will be of any suitable configuration so as to be effectively nested within the compass of the supporting structure without regard to the length and weight of the unsupported belt portion to be motivated in connection with its feeding into the gun. A feed assist mechanism of novel character is arranged between the magazine and the gun and is operatively coupled with the cartridge belt in such manner as to be adapted to take substantially all of the loads in connection with feeding the belt to the gun. The assist magazine is arranged to be of such character as to avoid overrunning the feed requirements of the gun feed mechanism per se; and thus uniform feeding of the gun is provided in an improved manner and jamming of the gun feed operation is avoided. Other objects and advantages of the invention will appear from the specification herein.

In the drawings:

Fig. 1 is a fragmentary side elevation of a machine gun and assist mechanism of the invention,

with portions broken away to reveal the interior thereof;

Fig. 2 is a view taken substantially along the line II—II of Fig. 1;

Fig. 3 is a view corresponding to Fig. 2 showing another form of assist mechanism;

Fig. 4 is a section, taken substantially along line IV—IV of Fig. 3;

Fig. 5 is a top plan of a machine gun and an assist mechanism control device of another form thereof; and

Fig. 6 is an enlarged view of the control device portion of Fig. 5, with portions broken away to reveal the interior thereof.

Fig. 7 is a diagrammatic view of the control switch and power circuit of the mechanism of Figs. 3 and 4; and

Fig. 8 is a diagrammatic view of the control switch and power circuit of the form of the invention illustrated by Figs. 5 and 6.

The invention is illustrated in Figs. 1 and 2 in conjunction with a machine gun 10 having a cartridge pawl 12 (Fig. 2) in association with the cartridge inlet port thereof, in accord with usual

machine gun practice. The cartridge belt magazine 14 is shown at a location spaced from the gun 10, and a belt feed assist mechanism of the invention is shown disposed between the gun 10 and magazine 14. The feed assist mechanism

includes a tubular throat piece 16 which is flared at its outer end 17 to provide smooth flow of the cartridge belt thereinto from the magazine 14. The magazine is also shown as being provided with rollers 18 for guiding the cartridge belt as it

emerges from the magazine in smoothly moving manner. The throat 16 is supported upon a bracket 19 so as to extend at its inner end portion 20 into registry with the cartridge inlet port of the gun 10, and it will be understood that the

throat 16 is of suitable rectangular sectional form and dimensions so as to freely accommodate the cartridge belt in smooth sliding relation therein. A pair of driving rolls 22—24 are rotatably mounted upon parallel shafts 26 and 27, respectively, so

as to be disposed in spaced relation and at opposite sides of the cartridge belt as it passes through the throat 16. The rolls 22 and 24 are provided with enlarged heads 28 at opposite ends thereof, and the heads 28 are peripherally escalloped as

illustrated in Fig. 2 so that the rolls 22 and 24 are adapted to engage the individual cartridges 30 of the cartridge belt as they pass therebetween in geared relation. The driving roll 24 is keyed to the shaft 26 which extends into connection with the inner end of a coil spring 34. The outer end

of the coil spring 34 is connected as at 35 to a cylindrical housing 37 which is in turn keyed at 38 to the driven shaft 40 of a reduction gear unit 42. The driving shaft 44 of the gear unit is operatively coupled with the armature of an electric motor 45 which is also mounted upon the bracket 19. The motor 45 is arranged to be energized from any suitable power source operating through a circuit controlled by the gun firing switch in such manner that whenever the gun firing switch is closed the gun will commence firing and simultaneously therewith the motor 45 will be energized to rotate the driving roll 24 through the coupling provided by the coil spring 34. Similarly, upon opening of the gun firing switch the motor 45 will be de-energized and cessation of the gun firing operation will be automatically accompanied by stopping of the motor driving action. Thus, the driving rolls 22-24 are adapted to feed the belt of cartridges 30 into the gun 10 generally in accord with its requirements, and to thus relieve the gun feed mechanism of the gun of the loads involved in pulling the belt out of the magazine 14 and into the feed throat 16.

Preferably, the motor 45 will be of the so-called high torque type and adapted to run at various speeds without damage to its windings, so that under relatively slow firing conditions the back pressure of the cartridge belt into the throat 16 will simply retard the speed of the driving motor. Preferably, the gear reduction device 42 will be of irreversible character so that reverse movement of the driving mechanism will not be possible when the motor 45 is de-energized. Thus, the device of the invention is adapted to provide a cartridge belt feeding operation which involves driving of the cartridge belt through the feed throat 16 upon operation of the driving motor 45, and simultaneous storing of energy within the coil spring 34, due to the attempt of the driving motor to overrun the speed of cartridge reception by the feed mechanism of the gun. Upon interruption of the gun firing operation the stoppage of the gun feed mechanism will immediately halt movement of the cartridge belt through the feed throat 16; and thus the driving rolls 22-24 will be halted while the momentum of the moving parts of the motor and associated driving mechanism will be dissipated in further tensioning of the coupling spring 34. Due to the irreversible character of the gear mechanism 42 the energy thus stored in the coupling spring 34 will be retained therein pending further operation of the gun. Upon subsequent reclosing of the gun firing switch and recommencement of the firing operation, the motor 45 will be re-energized, and while the motor 45 is picking up its full operating speed it will initially lag behind the required corresponding speed for feeding the cartridge belt in accord with the usual requirements of the gun. However, during this period of initial motor speed lag the coupling spring 34 will extend to make up for the deficiency in the driving motor speed, and thus there is provided an automatically uniform belt feeding pressure at all stages of the gun firing operation.

Figs. 3 and 4 illustrate another form of the invention wherein the feed assist mechanism is located between the magazine 14 and the gun 10 and includes a cartridge feed throat 50 which is generally similar to the feed throat 16 of Figs. 1 and 2. The throat 50 is rigidly mounted upon a fixed bracket 51. A pair of opposed driving rolls 52 and 54 which are generally similar to the driving rolls 22-24 hereinabove described are mount-

ed in similar relation except that the upper roll 54 is rotatably mounted upon the feed throat 50 and the lower roll 52 is rotatably mounted upon a yoke 56 which is in turn pivotally mounted by means of a pin 57 upon the bracket 51. A crank arm 58 extends below from the yoke 56 into pivotal connection at 59 with one end of a compression strut 60. The compression strut 60 is normally maintained in the condition illustrated in Fig. 3 by means of a compression spring 61 thereof; the strut 60 being pivotally mounted at its opposite end by means of a pin 62 to a portion of the fixed bracket 51. At its upper end and at a diametrical opposed location with respect to its connection at 59, the yoke 58 is arranged to bear against the extending finger portion 65 of a spring finger electric switch 66 which is mounted upon the bracket 51. Thus, the force of the compression spring 61 normally maintains the yoke 58 in the position of Fig. 3 whereby the lower roll 52 is in vertical alignment with the upper roll 54 and the finger 65 of the switch 66 is depressed in such manner as to close the electric circuit with which the switch 66 is associated. In Fig. 7 the switch 66 is illustrated as comprising a leaf spring contact member 67 adapted to be pressed by the finger 65 into contact with a fixed contact point 68 for closing the electric circuit controlling the driving motor which is illustrated in Fig. 4 at 70. A spring 69 is arranged to repel the finger 65 whenever the roll 52 is backed away from the switch as will be explained hereinafter. As in the case of the motor 45 of Figs. 1 and 2, the motor 70 is operatively coupled to an irreversible gear reduction device 72 by a drive shaft 73. The driven shaft 74 of the reduction gear device is operatively coupled through means of a pair of universal joints 75 and an intermediate drive shaft 76 with a torque tube 77 which is operatively connected to the inner end portion of a coil spring 78, as in the manner of the connection between the shaft 32 and the spring 34 of Fig. 1. The outer end portion of the spring 78 is fixed to a housing member 80 which is rotatably carried by means of a central bore upon a drive shaft 82 which extends into keyed relation with the driving roll 52. The drive shaft 82 is rotatably carried on opposed wall portions of the yoke 56, and thus the roll 52 is rotatably mounted upon the yoke. The housing 80 is connected at an extended central portion 84 to the inner end portion of a second coil spring 86 which is similar to the spring 78 and connects at its outer end to a second housing member 88. The second housing member 88 is keyed to the drive shaft 82 at 89.

Thus, beginning from a condition of non-operation, upon closing of the gun firing switch the machine gun 10 will commence firing and the recoil actuated cartridge feed mechanism thereof will operate to draw the belt of cartridges through the feed throat 50. Simultaneously with commencing of the firing operation of the gun, the motor 70 will be energized because of the closed circuit position of the switch 66. Thus, the motor 70 will operate through the gear and universal joint and spring coupling mechanism to rotate the drive shaft 82, whereupon the driving rolls 52 and 54 will operate to drive the cartridge belt through the feed throat 50 and to thus relieve the gun feed mechanism of the loads of drawing the cartridge belt out of the magazine 14. Subsequent to attainment of full driving speed on the part of the motor 70, the coupling spring devices 78 and 86 will operate to absorb overrunning movements of the motor 70 relative to

the cartridge belt feeding operation; and thus the coupling springs will be tensioned with roll driving energy. Upon interruption of the gun firing operation the movement of the cartridge belt to the feed throat 50 will be halted, but the motor 70 will continue momentarily to cause the driving roll 52 to be rotated. Since the belt of cartridges in the feed throat 50 is now positively halted because of stoppage of the gun feed mechanism, and because the drive shaft 82 of the roll 52 is mounted upon the pivotal yoke 56, the yoke 56 will then be caused to pivot upon the pin 57 against the action of the strut spring 61 to permit the upper end portion of the yoke 56 to move away from bearing contact against the actuating finger 65 of the switch 66. Thus, the circuit of the driving motor 70 will be interrupted and the motor de-energized. It will be understood that the pivoting movement of the yoke 56 and the consequent disalignment of the driving shaft 82 and the driven shaft 74 of the gear mechanism will be compensated for in the universal joints 75.

Subsequent to de-energization of the driving motor 70 the continued rotation of the motor and associated gearing because of momentum forces will be translated into further tensioning of the coupling spring devices 78-86; and the irreversible character of the gear mechanism 72 will prevent subsequent reversal of movement so that the coupling springs 78-86 will remain tensioned pending recommencement of the firing operation. Upon subsequent closing of the firing control switch and recommencement of the gun firing operation the action of the gun feed mechanism will initially relieve the congestion in the feed throat 50 and the roll carrying yoke 56 will be immediately allowed to pivot back to the position of Fig. 3 whereupon the control switch 66 will again be closed, thus completing the circuit to the driving motor 70 whereby the latter will again be energized. Prior to attainment of full driving speed on the part of the motor 70 the coupling spring devices 78-86 will extend from their previously tensioned conditions to make up for the deficiency of driving motor speed relative to the requirements of the gun feed mechanism. Upon subsequent attainment of full driving speed by the motor 70 the coupling spring devices will then function as simple driving elements; and thus the mode of operation will be repeated as above described until the contents of the magazine 14 are exhausted.

Also, it will be understood that by virtue of the arrangement of Figs. 3 and 4 the driving motor 70 is prevented from applying excessive torque to the driving roll 52 in relation to the cartridge feed requirements of the gun feed mechanism. Whenever the torque applied by the motor 70 to the driving roll 52 builds up to an excessive degree the reaction forces between the driving roller 52 and the cartridge belt portion between the rolls and the gun will automatically cause the roller 52 to rock the yoke about its pivot 57 out of engagement with the actuating finger of the switch 66, whereupon the motor 70 will be deenergized pending reduction of the torque applied through the driving mechanism to a degree consistent with the requirements of the cartridge feeding operation.

Figs. 5 and 6 illustrate another form of driving motor control device for the feed assist mechanism of the invention. The machine gun 10 is shown mounted upon a pair of stationary bearer tubes 100 which are in turn supported by any

suitable fixed base means (not shown). The gun 10 is provided at its rear end with a pair of laterally extending collars 101 which engage the bearer tubes in longitudinally free sliding relation. At its opposite end the gun casing is provided with a pair of opposed struts 102 which extend into corresponding end portions of the bearer tubes 100. The struts 102 are fitted with enlarged heads 103 at their inner ends which engage the inner walls of the bearer tubes 100 in free sliding relation. Compression springs 104 are arranged between the strut heads 103 and bearing plugs 104 which are fixed by means of pins 105 within the bearer tubes. Thus, the gun 10 is mounted upon the bearer tubes in such manner as to be slidably rearwardly thereon in response to recoil forces operating upon the gun during firing thereof, against the action of the compression springs 104. Preferably the adjacent end portions of the bearer tubes 100 will be closed with airtight inserts 106 and suitable packing as at 107. Thus, the air within the bores of the bearer tubes 100 in the region of the springs 104 will be compressed during recoil movements of the gun upon the bearer tubes, whereby the compression of the air will assist the springs 104 in cushioning the recoil forces of the gun and in returning the gun between firing operations toward its position of rest as shown in Fig. 6. However, the resiliency of the springs 104 and the air compressing operations are regulated in view of the rapidity of the firing of the gun so that the gun is not returned to its completely inactive position as illustrated in Fig. 6 between successive recoil strokes thereof. Hence, whereas the position of the extreme outer end of the strut 102 is illustrated in Fig. 6 as being in registry with line A thereof, the range of its recoil stroke positions during continuous firing of the gun will be as between lines B and C of Fig. 6.

40 A control switch 110 for controlling energization of the feed assist driving motor is fixedly mounted by means of a bracket 112 upon the insert 106 at the end of one of the bearer tubes 100 so as to be stationary and not subject to movement during recoil actions of the gun. A switch actuating finger 114 extends from the switch 110 into abutting registry at 115 with the adjacent strut 102 of the recoil mechanism of the gun mounting, and the switch actuating elements are so arranged that when the strut 102 is in the gun-inactive position of Figs. 6 and 8 the switch finger 114 is thereby maintained against the action of a spring device 115 within the switch 110 in such position as to allow the leaf spring contact member 116 to be away from the fixed contact member 117 so as to open the electric circuit controlled by the switch 110. Thus, whenever the gun 10 is inoperative the switch 110 is held open and the feed assist driving motor circuit is open. Upon commencement of the gun firing operation, however, the recoil strut 102 retreats to positions within the range of movement indicated by the lines B and C, thus (Fig. 6) allowing the finger 114 to move under the force of the spring 115 toward the right from the position of line A to the position of line D, whereupon the switch 110 will be actuated to close the circuit to the feed assist driving motor.

70 Thus, as long as firing of the gun continues the switch 110 remains closed, and the space between the contact finger 114 and the recoil strut 102 as marked between the lines D and C protects the switch finger 114 from hammering contact with the recoil strut during the gun firing operation.

Upon cessation of gun firing the gun returns to its position of rest relative to the bearer tubes 110 as illustrated by Fig. 6, whereupon the actuating finger of the switch 110 is moved by the recoil strut 102 to switch-off position, thus de-energizing the feed assist driving motor. Thus, the feed assist driving mechanism is automatically controlled by firing operation of the gun 10, and so long as the gun continues to fire the feed assist mechanism will continue to be energized by the driving motor. Thus, the energization of the feed assist mechanism is at all times a direct function of actual firing of the gun, and therefore the assist mechanism is operative only at such times as the gun requires feeding.

Although only a limited number of forms of the invention are shown and described in detail, it will be apparent to those skilled in the art that the invention is not so limited but that various changes may be made therein without departing from the spirit of the invention or the scope of the appended claims.

I claim:

1. A machine gun ammunition feed mechanism comprising a support, an ammunition belt guide mounted upon said support to extend into registry with the ammunition feed port of the machine gun, said guide comprising a conduit-like member adapted to slidably receive the belt in laterally confined relation, a belt driver movably mounted upon said support and extending into said conduit intermediate the ends thereof for driving engagement with the belt to force it to move through said guide in ammunition feeding direction toward said gun, motor means, elastic power transmission means coupling said motor means to said driver for actuating the latter to feed the belt through said guide toward the gun, elastic force means mounted upon said support and bearing against said driver to elastically urge said driver to positionally move in the direction of ammunition feeding toward said gun and to resist movement thereof in the direction opposite to the direction of belt feeding movement through said guide, and motor control means mounted upon said support in registry with said driver and adapted to be actuated thereby to cause said motor means to be de-energized upon movement of said driver against the action of said elastic means.

2. A machine gun ammunition belt feed mechanism comprising a support, an ammunition belt guide mounted upon said support to extend into registry with the ammunition feed port of the machine gun, said guide comprising a conduit-like member adapted to slidably receive the belt in laterally confined relation, a belt driver movably mounted upon said support and extending into said conduit intermediate the ends thereof for driving engagement with the belt to force it to move through said guide in ammunition feeding direction toward said gun, motor means coupled to said driver for actuating the latter to feed the belt through said guide toward the gun, said conduit-like member extending continuously to the feed port of the gun and constructed and arranged to constrain the feed belt to lineal feeding movement only, elastic force means mounted upon said support and bearing against said driver to elastically urge said driver to positionally move in the

direction of ammunition feeding and to resist positional movement thereof in the direction opposite to the direction of belt feeding movement through said guide, and motor control means mounted upon said support in registry with said driver and adapted to be actuated thereby to cause said motor means to be de-energized upon movement of said driver against the action of said elastic means.

3. A machine gun ammunition feed mechanism comprising a support, an ammunition belt guide mounted upon said support to extend into registry with the ammunition feed port of the machine gun, said guide comprising a conduit-like member adapted to slidably receive the belt in laterally confined relation, a belt driving sprocket movably mounted upon said support and extending into said conduit intermediate the ends thereof for geared engagement with the belt to force it to move through said guide in ammunition feeding direction toward said gun, motor means coupled to said sprocket for rotating the latter to feed the belt through said guide toward the gun, said conduit-like member extending continuously to the feed port of the gun and constructed and arranged to constrain the feed belt to lineal feeding movement only, elastic force means mounted upon said support and bearing against said sprocket to elastically urge said driver to positionally move in the direction of ammunition feeding and to resist positional bodily displacement movement thereof in the direction opposite to the direction of belt feeding movement through said guide, and motor control means mounted upon said support in registry with said sprocket and adapted to be actuated thereby to cause said motor means to be de-energized upon movement of said sprocket bodily against the action of said elastic means.

4. A machine gun ammunition feed mechanism comprising a support, an ammunition belt guide mounted upon said support to extend into registry with the ammunition feed port of the machine gun, said guide comprising a conduit-like member adapted to slidably receive the belt in laterally confined relation, a belt driver movably mounted upon said support and extending into said conduit intermediate the ends thereof for driving engagement with the belt to force it to move through said guide in ammunition feeding direction toward said gun, motor means coupled to said driver for actuating the latter to feed the belt through said guide toward the gun, said conduit-like member extending continuously to the feed port of the gun and constructed and arranged to constrain the feed belt to lineal feeding movement only, elastic force means mounted upon said support and bearing against said driver to elastically urge said driver to positionally move in the direction of ammunition feeding toward said gun and to resist bodily movement thereof in the direction opposite to the direction of belt feeding movement through said guide, and motor control means mounted upon said support in registry with said driver and adapted to be actuated thereby to cause said motor means to be de-energized upon movement of said driver against the action of said elastic means in response to increases of resistance by the gun to belt feeding operation of said driver.

JOHN C. TROTTER.
